UNITED STATES PATENT OFFICE.

JOHN F. O'CONNOR, OF CHICAGO, ILLINOIS, ASSIGNOR TO WILLIAM H. MINER, OF CHAZY, NEW YORK.

BRAKE-OPERATING MECHANISM.

1,300,466.

Specification of Letters Patent. Patented Apr. 15, 1919.

Application filed November 1, 1917. Serial No. 199,730.

To all whom it may concern:

Be it known that I, JOHN F. O'CONNOR, a citizen of the United States, residing at Chicago, in the county of Cook and State 5 of Illinois, have invented a certain new and useful Improvement in Brake-Operating Mechanism, of which the following is a full, clear, concise, and exact description, reference being had to the accompanying 10 drawings, forming a part of this specification.

This invention relates to improvements in railway hand brakes.

Heretofore, in the operation of railway 15 cars having hand operated brakes thereon, much difficulty and frequent danger have resulted to the brakemen because of the fact that, when the brakes are set, sudden unexpected movements of the car have thrown 20 the brakemen against the release dog of the brake mechanism, thus causing an accidental release of the brake mechanism and permitting the car to run unchecked into other cars or off the track.

25 The object of my invention is to provide a simple arrangement for positively preventing accidental release of the brake mechanism as hereinbefore described.

In the drawing forming a part of this 30 specification, Figure 1 is a vertical, sectional view, with the cover plate removed, of a hand brake suitable for railway cars, showing my improvements in connection therewith. Fig. 2 is a horizontal, sectional 35 view of the structure illustrated in Fig. 1 and taken on the line 2-2 thereof. And Figs. 3 and 4 are detail perspective views of the elements composing the locking and releasing dog.

40 In said drawing, 10 denotes a wall of a car to which my improved brake mechanism is adapted to be applied. The brake, as shown, comprises a housing casting 11 of horizontal substantially cylindrical form 45 having a plurality of flanges or ears 12 at its inner end by which it is adapted to be riveted or otherwise secured to the wall 10 of the car. The housing casting 11 is provided with suitable inner and outer bearings 13 and 14 for a chain winding drum 15, while the chain (not shown) passing up vertically through a suitable opening 16 in the housing casting 11 and winding over the drum 15. The drum 15, at its outer end, is 50 provided with a preferably integral ratchet

wheel 17 with which is adapted to coöperate a pawl 18 formed at the inner end of a gravity controlled, normally inoperative depending operating handle 19. The handle 19 is pivotally mounted, as indicated at 20, 60 on a hanger 21. The hanger 21 at its upper end is provided with a journal portion 22 rotatably mounted within a corresponding bearing 23 formed at the outer end of the drum 15, as clearly indicated in Fig. 2. 65 A cover plate 24 is employed to shield and protect the ratchet, hanger and pawl, said cover plate 24 and the other parts just mentioned, being held in properly assembled position by means of a bolt 25 which extends through the plate 24, through the hanger 21, through the drum 15 and through the wall 10, said bolt being retained by a nut 26 on the inner side of the wall 10. The chain is tightened or wound around the 70 drum 15 by oscillating the lever handle 19 in a well known manner which need not 75 here be described.

To retain the chain in its tightened condition, that is, with the brakes set, a pivoted 80 locking dog 27 is employed which is adapted to engage the ratchet 17, as illustrated in Fig. 1. Said dog 27 is maintained normally in operative engagement with the ratchet 17 under the influence of gravity, the arm 85 28 of the pawl which is extended outside of the housing casting, over-balancing the inner arm of the pawl. Pivotally connected to the pawl 27 is a short handle 29 which is arranged to depend normally, under the 90 influence of gravity, in the position shown in Fig. 1. When it is desired to release the ratchet, the operator swings the handle 29 to the position shown in dotted lines at 95 30 in Fig. 1, whereupon a shoulder 31 on the handle 29 will engage a coöperating shoulder 32 on the dog 27 and the latter may be readily disengaged from the ratchet. The handle 29 is so formed that, upon release of the same by the operator, it will fall to the 100 100 depending position shown in Fig. 1, so that it cannot accidentally ever be in the position shown by the dotted lines in Fig. 1.

With the arrangement above described, it is apparent that should the operator or 105 brakeman be accidentally thrown against the brake, he cannot thereby accidentally disengage the pawl 27 from the ratchet and release can only be effected intentionally by the operator or brakeman positively swing- 110

ing the handle 29 upwardly and thereby actuating the pawl 27. It will also be noted that the weight of the handle 29 serves to further over-balance the pawl 27 and automatically maintain the latter in operative engagement with the ratchet 17.

With the simple arrangement above described, I am enabled to overcome the disadvantages in prior brake structures hereinbefore referred to and without materially increasing the expense or the weight of the parts.

I claim:

1. In a hand brake for railway cars and the like, the combination with hand operated, chain tightening mechanism including a chain winding drum and a ratchet wheel, a pivotally mounted locking dog adapted to coöperate with said ratchet wheel to thereby maintain the chain in its tightened condition, said dog being pivotally mounted and normally held in operative position under the influence of gravity, and an operating handle pivotally attached to said dog, said operating handle being normally disposed in a depending position under the influence

of gravity but adapted to be manually elevated and, when in elevated position, arranged to move the pivoted dog to release the chain tightening mechanism.

2. In a brake mechanism adapted for railway cars, the combination with a substantially cylindrical casing adapted to be secured to the car wall, of a rotatable chain winding drum mounted within said casing, an operating handle for rotating said drum, a ratchet wheel rigid with said drum, a locking dog pivotally mounted within said casing and coöperable with said ratchet wheel to prevent accidental reverse rotation of the drum, said dog having its outer end extended slightly through an opening in the casing, and a handle pivotally attached to the exposed end of said dog, said handle normally hanging in a depending position, said handle being arranged to be swung upwardly to a substantially vertical position to release said dog.

In witness that I claim the foregoing I have hereunto subscribed my name this 29th day of October, 1917.

JOHN F. O'CONNOR.
